UNITED STATES PATENT OFFICE

2,576,815

FUSE PLUG CIRCUIT BREAKER

Edward V. Sundt, Chicago, Ill.

Application May 6, 1946, Serial No. 667,546

10 Claims. (Cl. 200—116)

1
The invention relates to circuit breakers and has particular reference to a very compact circuit breaker small enough to be inserted into an ordinary fuse socket.

Ordinary fuse plugs with a fusible metal insert have usually been resorted to for purposes for economy and convenience. Their most widespread use has been in house wiring circuits and similar types of circuits where the load on the electric system is not excessive. Fuse plugs of this type have the disadvantage in that once blown out the fuse plug must be thrown away and replaced with a new one.

Circuit breakers have long been known and have the advantage of being capable of resetting after they have been released to break the circuit because of an overload condition. Consequently, circuit breakers are capable of being used over and over again. On the other hand, circuit breakers have had the disadvantage in the past of being relatively high in initial cost which has prevented widespread use of them where loads are light and the cost of installation is a primary factor.

It is, therefore, among the objects of the invention to provide a new and improved circuit breaker which is sufficiently compact and inexpensive so that it can be used interchangeably with ordinary fuse plugs.

Another object of the invention is to provide a circuit breaker of such inexpensive construction that it can be used with economy in circuits where the load is light and the wiring is not extensive.

Still another object is to provide a circuit breaker for ordinary light capacity circuits which must be removed from the circuit before it is reset following the breaking of a circuit because of a "short" or an excessive load on the line.

The objects further contemplate a small compact plug type circuit breaker which is provided with a visible indicator to indicate when the breaker has been released and which also incorporates a means for adjusting the circuit breaker so that it can be actuated at different loads.

Further incorporated into the device is the provision of a means for reducing or minimizing arcing or flash when the circuit is broken or in the event that an attempt might be made to replace the device while the circuit is still shorted.

With these and other objects in view, the invention consists in the construction, arrangement and combination of the various parts of the device whereby the objects contemplated are at-

2
tained, as hereinafter more fully set forth, pointed out in the claims and illustrated in the accompanying drawings, in which:

Figure 1 is a longitudinal, sectional view of the device showing the circuit breaker in place in a fuse plug socket.

Figure 2 is a longitudinal, sectional view at right angles to the view shown in Figure 1 and taken on the line 2—2 of Figure 1 showing the circuit breaker removed from the socket.

Figure 3 is a cross-sectional view taken on the line 3—3 of Figure 1.

Figure 4 is a longitudinal view partly in section showing the circuit breaker in released position.

Figure 5 is a perspective view of the bimetallic element.

Figure 6 is an exploded view showing the parts which go to make up the circuit breaker.

Figure 7 is a top view of a modified form of the device incorporating an adjusting feature.

Figure 8 is a longitudinal view partially in section of the modified form taken on the line 8—8 of Figure 7.

Figure 9 is a longitudinal view partially in section showing still another modified form.

Heretofore it has been thought that in order to provide circuit breakers which would satisfy all of the requirements of a device for safely breaking the circuit under overload conditions that the mechanical parts of the device must be of heavy, rugged construction. Little thought has been given to economy of space and economy in the use of materials permitting the circuit breaker to be installed on 110 volts lines in ordinary lighting or light power circuits. To date the design of circuit breakers has been such that they could not be readily adapted to installations where they could satisfactorily substitute for the ordinary inexpensive fusible plug.

In an embodiment chosen to illustrate a compact design for a circuit breaker which is capable of being placed in the precise fixture originally designed for a fuse plug there is shown such a fixture comprising a base 10 of insulating material, a shell 11 of similar material and a metal screw socket 12 mounted within the shell 11. A binding post 13 is attached to a connection 14 communicating with the screw socket, and a binding post 15 is attached to a lead 16 which extends to the center of the screw socket.

The circuit breaker itself comprises a molded shell or casing 17 having a reduced portion 18 and an enlarged or head portion 19. Within the molded shell 17 is a chamber 20 occupying the

entire interior. The molded shell has a base or bottom 21 with a central aperture 22 extending therethrough and a translucent top or cover 23 of insulating material secured at its edge to the head of the molded shell by means of a flanged ring 24.

Within the aperture 22 is an eyelet 25 riveted over at both outside and inside ends. The eyelet is utilized as a means for firmly attaching a bimetallic member indicated generally by the character 26 in position at the bottom of the chamber 20.

As clearly shown in Figure 5, the bimetallic member comprises a bracket 27 constituting a base in which is a central aperture 28 adapted to receive the eyelet 25. At one end of the bracket is an outwardly extending leg 29, an outer portion of which terminates in a hooked end or extension 30. A second leg 31 is joined to the leg 29 adjacent the portion incorporating the hooked extension and extends inwardly to a point 32 adjacent to but spaced from the end of the bracket to which the leg 29 is attached. At the point 32 a resilient arm 33 is attached to the leg 31 so that there is a continuous electric connection. The arm is bowed around and has attached at its other end a bracket 34, the arm being provided with a recess 35 which assists in locating the bimetallic member by means of engagement with a rib 36 on the wall of the chamber 20. The bracket 34 has a platform 37 at the outer end which is adapted to rest upon a shelf or shoulder 38 and further assist in positively locating the bimetallic member.

The platform 37 provides one of two contact areas for the circuit breaker. On the side of the chamber opposite from the platform 37 is a right angular element 39 providing a second contact area, the right angular element having a leg 40 which extends along the outside surface of the reduced portion of the molded shell. A metallic screw shell 41 surrounds the reduced portion of the molded shell and is located in electric contact with the leg 40. The screw shell has an inwardly turned flange 42 of the conventional sort and snugly fits around the reduced portion of the molded shell so that it cannot be readily removed.

Within the chamber are parts of a movable device which constitute a latch member adapted to break the circuit. This includes a guide post 45 which extends axially throughout the length of the molded shell 17. The guide post has a reduced inside end 46 which extends slideably through the center of the eyelet 25. At its enlarged outer end the guide post is provided with a cup shaped reset button 47 which is provided with a flanged rim 48 located beneath the cover 23 and adapted to engage the underside of the cover in certain positions. The reset button extends slideably through a central aperture 49 in the cover and slides a limited distance relative thereto.

Contact is made between contact areas at 37 and 39 by means of a saddle 50. The saddle has a cup shaped central portion 51 centrally apertured so that it is adapted to slide over the outer end of the guide post and has one wing 52 adapted to rest upon the platform 37 and a wing 53 adapted to rest upon the angular element 39.

A coiled spring 55 bears at its lower end against the inside end of the eyelet 25 and against a washer 56 which abuts the bottom of the cup shaped portion of the saddle. A second coiled spring 57, somewhat heavier than the first, rests in the bottom of the cup shaped portion 51 of

the saddle on the side of the saddle opposite from the first spring.

Also located on the guide post surrounding the larger portion is a transverse latch element here illustrated as a disc 58, and beneath the disc is an insulating washer 54 separating the disc from the spring 57. The latch disc has a shank 59 on the outer side which slideably engages the interior of the setting button 47. It will be noted that the disc 58 has an undercut outer edge and that a portion of the edge, as viewed at the left side of Figure 2, is notched as at 60 so that the walls of the notch may engage a projection 61 on the interior of the chamber 20 for positioning and guiding the latch disc during its operation. The saddle is also provided with a notch 62 which likewise is adapted to engage and to be guided by the projection 61.

In operation the latch disc is normally set in the closed position best shown in Figure 2. In this position the hook end 30 overlies and engages the outer edge of the latch disc. Both springs 55 and 57 are contracted. The spring 55 tends to press upwardly against the saddle but the tendency is overcome by the greater pressure of the spring 57 which tends to press the saddle inwardly into a position where the wings 52 and 53 are in snug electric contact with the contact areas at 37 and 39.

In this adjustment current is adapted to flow from the binding post 15 through the eyelet 25, thence to the bracket 27 through the leg 29 of the bimetallic element, then through the leg 31, the arm 33, the bracket 34 and finally through the saddle to the right angular element 39 from whence it passes to the screw shell 41 and to the binding post 13. In this position of the saddle the circuit is complete through the bimetallic member.

When there is an overload in the line, the line heats up and so, also, the bimetallic member 26. As the legs 29 and 31 heat up they tend to bow outwardly so that the hooked extension 30 disengages itself from the edge of the latch disc. When disengagement is complete the latch disc is released, and the spring 55 then pushes the saddle outwardly so that the wings are disconnected from the contact areas and the circuit is broken. At the same time the spring 57 presses the latch disc, in company with the setting button, outwardly to the position shown in Figure 4 so as to afford a visual indication of the fact that the circuit is broken.

Inasmuch as there is a certain limited freedom of motion between the inside of the cup shaped portion of the setting button and the end of the flange on the latch disc, it is not possible to reset the latch disc beneath the hooked extension of the bimetallic member so long as the circuit breaker remains in position in the fixture.

In order to press the setting button inwardly, together with the guide post, far enough to reset the latch, the guide post must extend inwardly to the position shown in Figure 2. This is not possible when the guide post is prevented from extending inwardly by contact with the bottom of the fixture or socket. Once the latch disc has been set the circuit breaker may be screwed into the fixture or socket, and contact of the bottom of the guide post with the bottom of the fixture or socket will tend to lift the setting button a slight amount without disturbing the engagement of the latch disc with the bimetallic member.

In the embodiment shown in Figures 7 and 8 means is provided for shifting the latch disc in

such a manner that it will engage to a greater or lesser extent beneath the hooked end of the bimetallic member. By this device the circuit breaker may be set to release itself at a greater or lesser load increase, depending upon requirements.

In the modified form the principal operative parts of the device as a whole remain the same and are housed within the same molded shell. In order to provide an adjustment, however, the aperture 49' in a cover 23' is made slightly eccentric as is particularly apparent in Figure 7. The cover is designed to be held somewhat loosely in place at the top of the molded shell by means of a flanged ring 24' which is provided with a pointer 70 at one side. So that the pointer may remain in fixed position at all times, the molded shell is provided with a recess 14 within which a projection 75 on the flanged ring is designed to engage. The cover is provided with holes 76, for example, to which an instrument may be applied in order to rotate the cover.

Rotation of the cover changes the relative position of the eccentric aperture in the center. As the aperture shifts from one side toward the other the guide post will be tilted slightly from one substantially vertical position to another and thus change the location of the disc 58 relative to the hooked end 30 of the bimetallic element.

For example, in setting of the device illustrated in Figures 7 and 8 the eccentric aperture in the cover is moved to an intermediate position toward the left, and in this position the pointer 70 will coincide with a calibration 73 on the cover. At this setting the device will release under a load of intermediate magnitude.

To set the device for release under a heavy load, the cover is rotated, clockwise, until a calibration 71 coincides with the pointer. At this adjustment the eccentric aperture in the cover will have shifted toward the right, as viewed in Figure 8, although there may be some lateral shift with respect to the location of the bimetallic element. A shifted position is indicated by the dotted lines in Figure 8. Tilting the guide post moves the disc 58 so that it underlies the hooked end a greater amount. This means that in order to release the circuit breaker the load must be greater and cause a greater heating and subsequent bending of the bimetallic element.

Another intermediate release may be accomplished by setting the calibration 72 opposite the pointer 70, whereas, for lightest load a calibration 77 should lie opposite the pointer. By this simple means, therefore, the same circuit breaker can be set for release at various loads.

Although the circuit breaker has been shown primarily as one designed for incorporation into a molded shell of the size of a fuse plug, the same principles of design and construction could be incorporated into a circuit breaker having a casing of different proportions. An example of the latter construction is shown in Figure 9 wherein an insulating base 80 is provided with a housing 81 secured thereto which is adapted to receive complementary portions 82 and 83 of a casing housing moving parts of the circuit breaker. Within the casing is provided a bimetallic element 84 having a shape and construction similar to that described in the preferred embodiment and a contact bracket 85 making opposite points of contact for the wings of the saddle 50 in the manner described in connection with the preferred embodiment. The resetting button 47

and latch disc 58 function with the bimetallic element in the same manner as previously described.

Among the distinctions in the modified form shown in Figure 9 is the absence of a screw socket and the substitution therefor of contacts held in place by flanges at the edges of the complementary parts of the casing which in turn are anchored by the housing 81 secured to the base by screws 86.

By the provision of a circuit breaker in the compact design shown individual parts may be reduced to a minimum and made of inexpensive materials. Moving parts of the device are confined to a single member, and all are coaxially located about a single guide post. Assembly operations are thereby reduced substantially to a minimum, and there is provided an inexpensive circuit breaker which can be used in fixtures already designed for the reception of fuse plugs, the circuit breaker being capable of a simple resetting operation but with the added provision of making it necessary to remove the breaker from the short circuited line before the resetting operation is capable of being completed.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent structures.

The invention having been herein described, what is claimed and sought to be secured by Letters Patent is:

1. An electrical circuit breaker comprising a casing having a chamber therein, a first contact element on one side of the chamber and providing an external electrical connection, a second contact element on the opposite side of the chamber, a third contact element on another side of the chamber and providing another external electrical connection, a bimetallic thermostat element in the chamber having a latch shoulder and electrically connected between the second and third contact elements, a movable saddle adapted to engage and disengage the first and second contact elements to make and break an electric circuit between the first and third contact elements and through the bimetallic thermostat element, a spring engaging the saddle and adapted to disengage the saddle from the first and second contact elements, a movable latch member adapted to be latched by the latch shoulder of the bimetallic thermostat element, and a second spring between the latch member and the saddle for engaging the saddle with the first and second contact elements against the action of the first spring when the latch member is latched.

2. An electrical circuit breaker comprising a casing having a chamber therein, a first contact element on one side of the chamber and providing an external electrical connection, a second contact element on the opposite side of the chamber, a third contact element on another side of the chamber and providing another external electrical connection, a bimetallic thermostat element in the chamber having a latch shoulder and electrically connected between the second and third contact elements, a movable saddle adapted to engage and disengage the first and second contact elements to make and break an electric circuit between the first and third contact elements and through the bimetallic thermostat element, a spring engaging the saddle and adapted to disengage the saddle from the first and second contact elements, a movable latch member adapted to be latched by the latch shoulder of the bimetallic thermostat element, and a second spring between the latch member and the saddle for engaging the saddle with the first and second contact elements against the action of the first spring when the latch member is latched.

tact elements and through the bimetallic thermostat element, a spring engaging the saddle and adapted to disengage the saddle from the first and second contact elements, a movable latch member adapted to be latched by the latch shoulder of the bimetallic thermostat element, a second spring between the latch member and the saddle for engaging the saddle with the first and second contact elements against the action of the first spring when the latch member is latched, and an externally manipulated button extending into the chamber for moving the latch member into latching position.

3. An electric circuit breaker adapted to screw into a fuse socket comprising a casing having a chamber therein, a screw shell on the exterior of the casing, a first contact element on one side of the chamber electrically connected to the screw shell, a second contact element on the opposite side of the chamber, an eyelet extending through the bottom of the casing and forming a third contact element, a bimetallic thermostat element in the chamber having a latch shoulder and electrically connected between the second and third contact elements, a movable saddle adapted to engage and disengage the first and second contact elements to make and break an electric circuit between the first and third contact elements and through the bimetallic thermostat element, a spring adapted to disengage the saddle from the first and second contact elements, a movable latch member adapted to be latched by the shoulder of the bimetallic thermostat element, a second spring between the latch member and the saddle for engaging the saddle with the first and second contact elements against the action of the first spring when the latch member is latched, an externally manipulated button extending into the chamber for moving the latch member into latching position, and a post extending in said eyelet and engaging the button to prevent latching of the latch member and reengagement of the saddle with the first and second contact elements when the electrical circuit breaker is tightly screwed into the fuse socket.

4. An electric circuit breaker adapted to screw into a fuse socket comprising an insulating shell having a portion adapted to fit within a fuse socket and a chamber within the shell, a screw shell affixed to the insulating shell making an electrical contact for connection with the socket, a bottom contact eyelet at the center of the bottom of said insulating shell making an electrical contact for connection with the socket, a bimetallic thermostat element secured within the chamber by said eyelet and having a hooked extension and a contact element, an apertured top for the chamber, a central guide post having one end slidably endwise in said eyelet and the other end being slidable in the aperture of said top, a saddle slidably mounted on said guide post having ends in releasable electric communication respectively with the contact element and the screw shell, a latch element on said guide post having a portion releasably engaged beneath the hooked extension when in a set position, and opposed springs interposed between the saddle and adjacent portions of the circuit breaker adapted respectively to hold the saddle in electrical communicating and released positions.

5. An electrical circuit breaker adapted to screw into a fuse socket comprising an insulated shell having a portion adapted to fit within a fuse socket, a head portion and a chamber with-

in said shell, a screw shell affixed to said first portion making one electrical contact for engagement with the socket, a bottom contact eyelet at the center of the bottom of said shell making another electrical contact for engagement with the socket, a bimetallic thermostat element secured within the chamber by said eyelet having a hooked extension and a contact element, an apertured top for the chamber, a central guide post having one end slidably in said eyelet and the other end slidably received in the aperture in said top, a saddle slidably mounted on said guide post having opposite ends in releasable electric communication respectively with the contact element and the screw shell, a latch disc on said guide post having a lip releasably engaged beneath the hooked extension when in a set position, and opposed springs of different tension positioned between the saddle and respectively the latch disc and the eyelet adapted respectively to hold the saddle in electrical communicating and in released positions.

6. An electrical circuit breaker adapted to screw into a fuse socket comprising a casing, a screw shell on the exterior of the casing forming one electrical connection to the fuse socket, a central eyelet on the casing forming another electrical connection to the fuse socket, a releasable overload switch in the casing including a contact member movable to electrically connect the eyelet and the screw shell, means for actuating said releasable overload switch including a post member slidably mounted in the casing and on which post member the contact member is slidably mounted, said post member being of greater length than the casing so that at least one terminal portion of the post member extends from the casing at all times, spring means mounted on the post member at opposite sides of the contact member, means carried by the post member and operable through one of said springs when the post member is moved in one direction to move the contact member to circuit closing position, current responsive latch means for engaging said contact member moving means to latch the contact member in circuit closing position against the tension of the other of said spring means, a button engaging one end of the post member and extending through a wall of the casing at all times for so moving the post member, the opposite end of the post member being projected from said casing within the area thereof which is adapted to be received in said fuse socket when in service, before the contact member moving means of the post member reaches latched position whereby to prevent closing the circuit breaker when the casing is within such socket, and a lost motion connection between the post member and said contact member moving means to permit sliding movement of the post member in the opposite direction after the latch is engaged.

7. In an electric circuit breaker, a substantially cylindrical shell member having a cavity, spaced electric contact elements in said cavity, a post assembly mounted in said cavity and axially slidably with respect to the shell, said post assembly including a post member having one end thereof disposed substantially on the axis of the shell, a contact member, and a latch member, the contact member and the latch member being slidably mounted on the post member, said post assembly when the circuit breaker is in service, being normally latched in position in which the contact member is in circuit closing relationship with said contact elements, a spring

urging the post assembly and said contact member out of circuit closing relation, a guide member in said shell for the other end of the post member, said guide member having a guide opening in which said other end of the post is engaged, said opening being eccentrically disposed relative to the axis of the shell and guiding the axially slidable movement of the post, a bimetallic hook member mounted in said shell and in circuit with said contact elements, said hook member having a portion in overlying, transversely slidable engagement with the latch member of the post assembly and adapted to bow out of engagement therewith under the heating influence of an increased electric current flowing through the hook member, means mounting said post guide member for rotation about the axis of the shell, said guide member having a plurality of settings for varying the degree of overlapping engagement between the hook and the latch member of the post assembly for release of the engagement at different current loads.

8. In an electric circuit breaker a shell having a cylindrical side wall, a bottom, and a cover rotatably mounted relative to the side wall, said bottom having a central aperture therein and said cover having an eccentrically located aperture therethrough, a pair of electric contact elements in said shell, a post extending slidably through said apertures, a contact member mounted on said post and movable to circuit-closing relationship with said contact elements when the post is moved in one direction, and a spring normally urging said post in the opposite direction and said contact member out of circuit closing relationship, shoulder means on said post, a bimetallic hook in circuit with said contact elements and mounted in the shell, said hook having a portion overlying and in transversely slidable engagement with the shoulder means and adapted to bow out of engagement under the heating influence of an increase in electric current flowing therethrough, said cover having a plurality of positions of rotative adjustment for varying the degree of eccentricity of said post and the shoulder means thereon, with respect to the axis of the shell to thereby adjust the degree of overlap of said hook and shoulder means to provide for release of the hook at different current loads.

9. In an electric circuit breaker comprising an insulating shell having a chamber therein, a cover for the chamber, electric current controlling contact elements and a current carrying assembly including a bimetallic member in circuit with the contact elements and having a latch hook thereon, the combination of a contact operating and position indicating latching unit disposed within the chamber and including a post member and a contact member slidably mounted thereon, and means for operating the contact member to and from circuit closing position with respect to the contact elements, a latch member slidably mounted on the post member for engaging the latch hook, said latch member having a

sleeve portion surrounding one end of the post member, means for normally urging the latch member outwardly, means for normally urging said contact member to circuit open position, and 5 a visible, flanged, cupped, reset button secured to said one end of said post member and slidably encompassing the sleeve portion of the latch member and slidably located in an opening in the cover, said button being depressable to move the 10 latch member inwardly into latching engagement with said latch hook and the contact member into circuit closing position with the contact elements, and being movable by said latch member moving means to an extended position beyond 15 the cover with the flanged portion of the button in engagement with the cover when the latch is released and the contact member opens the circuit through the circuit breaker.

10. In an electric circuit breaker, a shell, an 20 elongated member mounted therein for endwise movement, spaced apertured guide means within the shell and slidably engaging opposite end portions of said elongated member, a pair of spaced contacts within the shell, and a movable contact 25 member cooperating therewith to open and close a circuit therebetween, means operatively connecting said contact member and said elongated member whereby endwise movement of the elongated member is effective to operate the contact 30 member to circuit closed position, spring means urging the elongated member in a direction in which the contact member is in circuit open position, a latch member mounted on the elongated member and movable therewith, a bimetallic 35 member within the shell and in circuit with said spaced contacts, said bimetallic member including a latch engaging portion normally disposed in the path of movement of said latch member and operable when the latch parts are engaged to retain the latch member and said contact member 40 in circuit closing position against movement under the influence of said spring, and eccentric mounting means for one end of said guide means for controllably laterally shifting one end of the 45 elongated member with respect to the other to variably tilt the axis thereof towards and away from said bimetallic member to thereby vary the degree of overlap between the latch portion of the bimetallic member and the latch member and 50 thus set the latch for release at different conditions of overload.
